UNITED STATES PATENT OFFICE.

HUGO PETERSEN, OF WILMERSDORF, NEAR BERLIN, GERMANY.

MANUFACTURE OF SULFURIC ACID.

No. 904,147.

Specification of Letters Patent.

Patented Nov. 17, 1908.

Application filed January 2, 1907. Serial No. 350,552.

To all whom it may concern:

Be it known that I, HUGO PETERSEN, a chemical engineer, and a subject of the German Emperor, and a resident of 181 Kaiser-alleé, in the city of Wilmersdorf, near Berlin, Kingdom of Prussia, and German Empire, have invented certain new and useful Improvements in the Manufacture of Sulfuric Acid, of which the following is a specification.

This invention has reference to improvements in the art of manufacturing sulfuric acid by the lead-chamber method, and it is intended to avoid the difficulties which are caused by the escape of unconverted sulfur-dioxide or of an excess of oxids of nitrogen from the last chamber, as it occurs for instance in the so-called system of forced working of lead chambers, or in the case of a great increase of the amount of nitric acid fed to the lead-chamber system, and in the case of irregularly burning sulfid-ores.

On the accompanying sheet of drawing, a plant for carrying the invention into practice, is shown diagrammatically by way of example in Figure 1 in plan view, and in Fig. 2 in side view.

In the drawing:—*a* indicates the kiln for generating sulfur-dioxide gases; *b* indicates the Glover-tower which is rinsed in the usual manner, well-known in the art, with sulfuric acid containing dissolved oxids of nitrogen, that is to say with the nitrous vitriol, produced at the foot of the Gay-Lussac-tower *g* and fed to the top of the said Glover tower by the conduit *o*. The lead chambers into which the gases pass from the Glover tower, are indicated at *c* and *d*, while *e* is another lead chamber of smaller size than the lead-chambers *c*, *d*. The gases are then passed into what I may call a "regulator" *f* which is shown in the drawing, as being an acid tower. This tower *f* is rinsed with cold nitrous vitriol of about fifty-five degrees Baumé. The acid which passes off at the foot of this tower, after it has come in contact with the gases, immediately leaving the last lead chamber, is run into a tank or cistern *h*, whence it is pumped back again, through the conduit *i* to the top of the said "regulator" tower *f*, so as to circulate over and over again on said tower, its strength being corrected and adjusted from time to time by suitable additions of acid or of nitrous vitriol, so as to maintain the proper concentration. In case the strength of the rinsing

acid of the said tower *f* should have gone down too far, the acid is exchanged for entirely fresh rinsing acid, that is to say for a fresh supply of cold nitrous vitriol of about 55 degrees Bé. *g* indicates the Gay-Lussac-tower from the foot of which the nitrous vitriol which possesses the ordinary strength of about 60 degrees Baumé is passed to the top of the Glover tower *b*. *h* and *n* are acid pumps or acid eggs, arranged in suitable places on the above mentioned acid conduits. *m* is the conduit for carrying the strong de-nitrated acid from the bottom of the Glover tower *b* to the top of the Gay-Lussac-tower *g* for the purpose of rinsing said Gay-Lussac-tower. The direction of the flow of the liquids is indicated by arrows in the drawing.

In case any unconverted sulfur-dioxide gases should escape from the last lead chamber, they are immediately converted into sulfuric acid by the cold nitrous vitriol of about 55 Bé., of the "regulator" tower *f*, the sulfuric acid formed going to compensate the acid diluting influence of the water vapors escaping from the last chamber and passing into the regulator-tower likewise. The nitrogen-oxid gases, liberated in the regulator-tower *f* by the said formation of sulfuric acid are absorbed in the following Gay-Lussac-tower or towers. By the formation of sulfuric acid, the rinsing acid of the "regulator" tower *f* becomes better adapted for the absorption of an excess of nitrogen-oxids, thereby increasing its own percentage in nitrogen-oxids. Inasmuch, as in those cases, where unconverted sulfur-dioxide gases escape from the last lead-chamber, this difficulty is usually corrected by increasing the addition of nitric acid to the top of the Glover tower, the escape of sulfur-dioxide gases from the last lead-chamber will be followed in a subsequent stage by an increased amount of oxids of nitrogen escaping from the last lead-chamber. This increased quantity of nitrogen-oxids is then absorbed by the rinsing acid of the "regulator" tower *f* which has increased its strength in sulfuric acid in the previous stage. Thus the treatment of the gases, escaping from the last chamber, with cold nitrous vitriol of about 55 Bé. strength acts as a means of regulating the lead chamber process, and of preventing both escape of unconverted sulfur-dioxide gases, as well as escape of unused oxids of nitrogen from the system. Nitrous vitriol of about fifty-five degrees

Baumé strength possesses the property of absorbing nitrogen oxids very readily in the cold, and of parting with the said oxids absorbed just as readily, and without the necessity of any great dilution or of heating of the nitrous vitriol, as distinguished from the ordinary strong nitrous vitriol, used as an absorbent on the Gay-Lussac-towers.

What I claim and desire to secure by Letters Patent of the United States, is:—

The improvement in the art of manufacturing sulfuric acid by the lead chamber method, said improvement consisting in

bringing the gases in contact with cold nitrous vitriol of about fifty-five degrees Baumé, immediately after the gases have left the last lead chamber and prior to the Gay-Lussac treatment, substantially as and for the purpose described.

In testimony whereof I have affixed my signature to this specification in presence of two subscribing witnesses.

HUGO PETERSEN.
